Inventor:
ALFRED A. JOHNSON

By
Baldwin Vale attorney

UNITED STATES PATENT OFFICE.

ALFRED A. JOHNSON, OF CHICO, CALIFORNIA.

TOOL FOR PULLING GEARS, ETC., FROM THEIR SHAFTS.

Application filed February 10, 1921. Serial No. 444,020.

To all whom it may concern:

Be it known that I, ALFRED A. JOHNSON, a citizen of the United States, and a resident of the city of Chico, county of Butte, State of California, have made a new and useful invention—to wit, Improvements in Tools for Pulling Gears, Etc., from Their Shafts; and I do hereby declare the following to be a full, clear, concise, and exact description of 10 the same.

This invention relates particularly to an improved device for moving one element relative to another.

The principal object of my invention is to 15 provide an improved tool or device for moving or separating pulleys, wheels, gears and the like from shafts or pintles to which they might be attached. A further object of my invention is to provide an appliance that 20 may be readily placed into or out of operative position relative to the parts on which it is to operate, and that may be easily transported and economically manufactured. Other objects and advantages will appear as 25 this description progresses.

In this specification and the annexed drawings, the invention is illustrated in the form considered to be the best, but it is to be understood that the invention is not limited to such form, because it may be embodied in other forms, and it is also to be understood that in and by the claims following the description, it is desired to cover the invention in whatsoever form it may be 35 embodied.

This invention is known primarily as a gear puller and is used for the purpose of drawing pulleys, wheels, cams or other parts from a shaft or bar and which fit so snugly, 40 or tightly as to resist removal by any of the ordinary methods. As a usual matter, the removal of an article from its semi-permanent position necessitates the use of a pressure tool with leverage means strong enough 45 to overcome the friction holding the said article in place. The usual method of having but one threaded shaft is objectionable in that the thread may be stripped or if a coarser thread used, the mechanical ad- 50 vantage is insufficient. The accompanying specification refers to an improved appliance that is intended to overcome all of the ob- 55 jectionable features found in the present type of gear puller.

In the accompanying one-sheet of draw- 55 ings,

Figure 1 represents a plan view of a tool constructed in accordance with my invention showing its method of operation.

Figure 2 is a plan view of Figure 1.

In detail the construction illustrated in the drawings consists of a body member or "strong-back" generally designated by the numeral 1 and provided with a plurality of slotted portions 2, 3 and 4 thereon. It is to be understood that I do not limit the number of slotted portions to the quantity shown for it would be clearly within the purview of this invention to re-arrange the positions of the slotted members relative to the axis 70 of the body portion 1, to increase or lessen the number thereof. The slotted portions 2, 3 and 4 are formed integrally with the body member 1 and have arms 5, 6 and 7 arranged thereon by passing suitable pivot pins 8, 9 75 and 10 through suitable openings provided in the portions 2, 3 and 4 and in the ends of the said arms. The opposite ends of the arms are either formed hook-shape or in any other desirable contour best suitable for 80 the purpose to which the appliance is used.

The body portion 1 is drilled concentrically and threaded to permit the interiorly and exteriorly threaded sleeve 11 being placed into engagement therewith. The 85 sleeve 11 is provided with a squared portion 12 on an end thereof to afford a grip to a wrench or other turning device. In the practice of this invention, the exteriorly threaded portion of the sleeve 11 would be 90 provided with threads of a standard of substantially five to the inch. The interior portion of the sleeve 11 would be threaded with a slightly finer thread of a standard of substantially six to the inch. Although I have 95 indicated that the shaft and sleeve should be provided with threads of a certain pitch, I do not wish to limit myself to the sizes shown as it would be clearly within the purview of this invention to vary the respective 100 thread pitches so long as the ratio between the same would be maintained. A central threaded shaft 14 is adapted to be placed into engagement with the interiorly threaded portion of the sleeve 11, the shaft 14 being provided with a tapered point on the end thereof for centering purposes and the opposite end 16 squared or otherwise formed for wrench engagement.

Assuming that a gear, wheel or other 110 article 17 were to be removed from a shaft or bar 18, the part 17 ordinarily being

movable relative to the remaining part 18, the shaft 14 of the tool would first be placed against the end of the shaft 18 and the clamping arms 5, 6 and 7 into engagement with the part 17 to be removed. In this position the operator would move the shaft 14 so as to gradually increase the gripping tension of the arms 5, 6 and 7 on the article 17. If the gear 17 had become rusted and very securely held to the shaft 18, the operator would rotate the sleeve 12 for the reason that owing to the differential relation existing between the shaft 14 and sleeve 11 with threads of different pitches, a far greater mechanical advantage is obtained. After the gear 17 becomes sufficiently loosened, the operator would discontinue rotating the sleeve 11 and apply the rotative movement to the shaft 14 and through the single threads thereof would obtain a faster movement of the movable element relative to the stationary part. The arrangement of the adjusting screws with standard threads of different pitch permits a more efficient leverage working force to be obtained, thus accomplishing greater results with less labor and in much quicker time.

Having thus described this invention, what I claim and desire to secure by Letters 30 Patent is:

1. A device of the character described comprising a body member having a plurality of slots therein; hooked members arranged in said slots; a threaded member ad- 35 justably positioned in said body member

and movable axially relative thereto for imparting axial movement to said hooked members and an auxiliary threaded member mounted within said first mentioned threaded member and movable axially relative thereto for imparting axial movement to said body member. 40

2. A device of the character described comprising a body member having a plurality of slots therein; hooked members arranged in said slots; and plural threaded means mounted within said body member and movable axially relative thereto at different rates of speed for imparting an axial movement to said hooked members. 45

3. An appliance such as described for moving one element relative to another comprising a member provided with elongated openings therein and having a plural threaded means mounted within said body member, each of said threaded means being movable axially relative to the body member and to each other at different rates of speed, and one of said threaded means engaging one of said elements and arms 50 mounted in said elongated openings and having the opposite ends thereof adapted to engage the other of said elements. 55

In testimony whereof, I have hereunto set my hand at Chico, California, this 31 day 60 of January, 1921.

ALFRED A. JOHNSON.

In presence of—
H. K. SEARS.
